MUSIC LEAF TURNER.

APPLICATION FILED JUNE 28, 1907.

2 SHEETS—SHEET 2.

UNITED STATES PATENT OFFICE.

AL H. LAMB, OF ELBON, PENNSYLVANIA.

MUSIC-LEAF TURNER.

No. 887,334.

Specification of Letters Patent.

Patented May 12, 1908.

Application filed June 28, 1907. Serial No. 381,344.

To all whom it may concern:

Be it known that I, AL H. LAMB, a citizen of the United States, residing at Elbon, in the county of Elk and State of Pennsylvania, have invented a new and useful Music-Leaf Turner, of which the following is a specification.

The invention relates to improvements in music leaf turners.

10 The object of the present invention is to improve the construction of music leaf turners, more especially that shown and described in Patent, No. 729,944, granted to me June 2, 1903, and to provide a simple and comparatively inexpensive construction, adapted to enable a plurality of sheets or leaves to be successively turned, and capable, when operated, to turn the leaves in either direction of presenting to the front, in position for operation, a set of finger pieces for moving the leaf turning means in the opposite direction.

With these and other objects in view, the invention consists in the construction and novel combination of parts hereinafter fully described, illustrated in the accompanying drawings, and pointed out in the claims hereunto appended; it being understood that various changes in the form, proportion, size and minor details of construction, within the scope of the claims, may be resorted to without departing from the spirit or sacrificing any of the advantages of the invention.

In the drawings:—Figure 1 is a front elevation of a music leaf turner, constructed in accordance with this invention. Fig. 2 is a rear elevation of the same. Fig. 3 is a vertical sectional view, showing the music leaf turner applied to a portion of a piano. Fig. 4 is an enlarged vertical sectional view, illustrating the arrangement of the gearing for oscillating the leaf turning arms. Fig. 5 is a front elevation of the same. Fig. 6 is a sectional view, taken substantially on the line $x-x$ of Fig. 5. Fig. 7 is a detail view, taken substantially on the line $y-y$ of Fig. 2.

Like numerals of reference designate corresponding parts in all the figures of the drawings.

1 designates the back or body of the music leaf turner, which back or body 1 may be constructed of any suitable material, such as wood or metal, and it may be ornamented in any preferred manner. The music leaf turner, which is designed for use on pianos and similar instruments, may also be ad-

vantageously employed in various other places, where it is desirable to turn sheets or leaves of music. In order to enable it to be conveniently mounted on a piano 2, as illustrated in Fig. 3 of the drawings, it is provided at the bottom with a rear spring 3, constructed substantially the same as that shown in the said patent, and an adjustable bar 4 is also provided for engaging the upper portion of the piano. The adjustable bar 4, 60 which operates in a suitable guide 5, is secured in its adjustment by a set screw 6, and it is provided at its upper end with a suitable head 7 for engaging under a projecting front edge of the top of the piano. The guide 5 is composed of spaced sides or flanges suitably secured to the rear face of the back or body 1. This guide 5 is secured to the rear face of the back or body by means of transverse straps or pieces 8, 9 and 10. The set screw is 70 mounted on the top strap or piece 8, and it engages the adjacent side or flange of the guide 5, a suitable threaded perforation being provided in the top strap or piece 8. The adjustable bar is adapted to be raised or 75 lowered to enable the music-leaf turner to be securely mounted on a piano, or similar instrument. Any other suitable means may be employed for mounting the music-leaf turner on either an instrument or a stand, as 80 will be readily apparent.

The music-leaf turner forms a music rack and for this purpose is provided with side clamps 11, and a central clamp 12. The side clamps 11, which are adapted to engage 90 the front and rear leaves of a piece of sheet music, or the front and rear portions of a music book, or the like, are constructed of resilient wire, or other suitable material and extend upwardly and downwardly, as clearly 95 illustrated in Fig. 1 of the drawings. The lower terminals of the material of which the side clamps are constructed are bent to form eyes 13 to receive screws 14, or other suitable fastening devices for securing the side clamps 100 to the back or body. The upper portions of the side clamps are adapted to be sprung away from the back or body to permit the leaves or sheets of music to be placed back of the side clamps in position to be engaged by 105 the same.

The central clamp consists of a pivoted rod or member, extending upwardly from the lower portion of the back or body at the center thereof and provided at its lower end 110

with a head 15, through which passes a pivot 16, which is mounted in a substantially U-shaped bracket or piece 17, secured to the front face of the back or body and consisting of spaced sides and a connecting bottom portion. The space between the sides of the bracket 17 registers with a slot 18 of the back or body and the head 15, which is beveled or rounded at the front, is provided with a straight rear edge and is adapted to be engaged by a spring 19, whereby the central clamp is held either in or out of engagement with the music. The spring 19, which may consist of one or more leaves, is secured to the rear face of the back or body and is provided with a head 20 for engaging the head of the central clamp 12. The head 20 of the spring is beveled, as clearly shown in Fig. 3 of the drawings, and the spring is of sufficient strength to maintain the central clamp firmly in engagement with the music, and it permits the central clamp to be readily swung downward to nearly a horizontal position to enable a music book or piece of sheet music to be placed on or removed from the music-leaf turner. The back or body of the music-leaf turner is also provided with a plurality of pins or projections 20^a to support the lower edges of the leaves to relieve the central and side clamps of the weight of the music.

The leaves or sheets of music are swung from one side to the other of the back or body by means of a plurality of leaf turning arms 21 to turn the sheets or leaves. The leaf turning mechanism is mounted on and carried by a bearing bracket 22, which is detachably secured to the back or body of the music leaf turner by screws 23, and which may be readily applied to any music rack. The bearing bracket, which is composed of a back portion and top and bottom portions is provided with a transversely curved front plate 24. The leaf turning arms, which are substantially L-shaped, are provided at the inner ends of their horizontal portions with heads 25 and 25^a, having openings of progressively increasing diameters to fit an inner central supporting shaft or spindle 26, and a plurality of nested or telescoped tubular shafts or sleeves 27, 28, 29, and 30. The shaft or spindle and the sleeves are mounted in the bearing bracket, and the sleeves are successively terminated short of one another, as clearly illustrated in Fig. 4 of the drawings to permit the leaf turning arms to be arranged one upon another and to swing in different planes, so as not to interfere with one another. The shaft or spindle 26 extends beyond the sleeves, and the sleeve of the smallest diameter is arranged on the shaft or spindle. Each sleeve turns independently of the other and the shaft or spindle rotates independently of the sleeves. The head 25 of the leaf turning arms is provided with a set screw 31 for en-

gaging the shaft or spindle 26, and other heads 25^a are split to form clamping jaws, which are connected by screws 31^a. The shaft or spindle and the tubular shafts or sleeves are partially rotated to swing the arms from one side of the music leaf turner to the other by means of pinions 32 and toothed segments 33. The pinions, which are of the same diameter, are secured to the shaft and to the sleeves and arranged in spaced relation. The toothed segments 33 are mounted on a spindle or pivot 34 and are provided with spaced sleeves 35 to maintain them in proper position with relation to the spaced pinions. Each segment 33 is provided with opposite arms 36, having finger pieces 37 and located at opposite sides of the pivot and movable backwardly and forwardly in reverse direction, so that when the arm at one side of the segment is moved rearwardly to swing the leaf turning arm in one direction, the operating arm 36 at the opposite side of the segment will be swung outwardly to the front of the bearing bracket and will be in position for operation to move the leaf turning arm in the opposite direction. By this arrangement one of the finger pieces of each leaf turning arm will always be at the front in position for operation. The oscillatory movements of the segments 33, which mesh with the pinions, partially rotate the same and operate the shafts to which the leaf turning arms are connected. In swinging the music from right to left the entire set of leaf turning arms may be simultaneously operated, and as the operating arms and their finger pieces are arranged at different elevations, the leaf turning arms may be successively actuated with rapidity and certainty. The curved front plate 24 of the bearing bracket is provided with opposite slots 38 to receive the operating arms.

Having thus fully described my invention, what I claim as new and desire to secure by Letters Patent, is:—

1. In a device of the class described, the combination with a back or body provided with a spindle, of a plurality of leaf turning arms provided with heads arranged on the said spindle, a plurality of pinions also mounted on the said spindle and connected with the said heads, a separate spindle or shaft mounted on the back or body, and toothed segments mounted on the last mentioned shaft or spindle and meshing with the pinions, each segment being provided with a pair of operating arms rigid with and extending in opposite directions from the segment and arranged so that when one arm of the segment is moved rearwardly the other arm of the same will be moved forwardly.

2. In a device of the class described, the combination with a back or body provided with a spindle, of a plurality of leaf turning arms having their lower ends bent forwardly

110

115

and provided with heads arranged on the said spindle, a plurality of pinions also mounted on the said spindle, a series of nested tubular shafts arranged on the spindle 5 and connecting the heads and the pinions, a second spindle or shaft mounted on the said back or body, and toothed segments mounted on the last mentioned shaft or spindle and meshing with the said pinions, each segment 10 being provided with a pair of operating arms rigid with and extending in opposite directions from the segment and arranged so that when one arm of the segment is moved rearwardly the other arm of 15 the same will be moved forwardly.

3. In a device of the class described, the combination of a plurality of leaf turning arms, a series of nested shafts carrying the arms and consisting of an inner supporting 20 spindle and a plurality of sleeves of different lengths and diameters, pinions mounted on the spindle and the sleeves, a pivot located in advance of the pinions, toothed segments meshing with the pinions and having sleeves 25 mounted on the said pivot, and opposite operating arms extending from the segments and movable backwardly and forwardly in reverse directions, so that one of the operat-

ing arms of each segment will always be in position for operation.

4. In a device of the class described, the combination with a back or body, of a bracket mounted on the back or body and provided with front and rear spindles, a series of nested tubular shafts mounted on the rear 30 one of said spindles, a plurality of leaf turning arms provided with heads secured to the upper ends of the nested shafts and arranged above the bracket, pinions arranged within the bracket and mounted on the nested shafts, toothed segments mounted on the front spindle and meshing with the pinions and each, provided with a pair of operating arms rigid with and extending from opposite sides of the segment, so that when one arm 35 of the segment is moved rearwardly the other arm of the same will be moved forwardly, and sleeves also mounted on the front spindle and spacing the segments.

In testimony, that I claim the foregoing 40 as my own, I have hereto affixed my signature in the presence of two witnesses.

AL H. LAMB.
